PICK-OFF MEANS FOR GUMMING MACHINES

George W. von Hofe, Bound Brook, N. J., assignor
to New Jersey Machine Corporation, Hoboken,
N. J., a corporation of New Jersey

Application September 14, 1934, Serial No. 743,930

6 Claims. (Cl. 91—58)

My invention relates to gumming machines for applying adhesive to sheets of paper or other material, which machines usually include a gumming roll against which individual sheets or their equivalent are fed and whereby the adhesive is applied to said sheets or other material. Such machines further generally include a pick-off means for stripping the adhesive coated sheets from the gumming roll and a reversing roll co-operating with a deflecting means whereby the travel of the sheets or other material from the gumming roll is controlled.

In existing machines of the indicated type, the deflecting means and the pick-off means are fixed relatively to each other and the extreme point of the latter alone rests upon the surface of the gumming roll. These points are subject to constant wear and consequently soon become inefficient in action and require frequent sharpening to avoid tearing or crumpling of the sheets or other material and resulting clogging of the machine. Continuous wear and repeated sharpening of the points of the pick-off means tend to bring the latter, of which there are several in a given machine, out of alignment with each other with the result that the wet sheets or other material are unevenly engaged and are torn or wrinkled, thus bringing about a defective operation or clogging of the machine.

The object of the present invention is to provide a pick-off means of improved and simplified construction in which existing objections and disadvantages are avoided and which operates in an efficient manner for maximum periods of time without replacement. The invention further contemplates the provision of an improved construction in which replacement, when required, may be efficiently effected in a minimum of time and with a minimum of effort. Other more specific objects will appear from the description hereinafter and the features of novelty will be pointed out in the claims.

In the accompanying drawing, which illustrates an example of the invention without defining its limits, Fig. 1 is a fragmentary sectional view of a gumming machine with a selected form of the novel pick-off means embodied therein; Fig. 2 is a fragmentary plan view; Fig. 3 is a detail sectional view on the line 3—3 of Fig. 1, and Fig. 4 is a perspective detail view of the pick-off member.

The fragmentary view of the gumming machine illustrated in Fig. 1 of the drawing shows a gumming roll 5 of any customary construction and mounted in the machine in any conventional

manner; this gumming roll 5 may itself dip into a supply of suitable adhesive or, as shown in Fig. 1, may have rolling contact with a transfer roll 6 adapted to transfer adhesive from a supply thereof to the surface of the gumming roll 5 in any suitable manner. The machine may further include a stationary bar 7 across which the sheets of paper or other material 8 may be fed in the direction of the arrow a, to the gumming roll 5 as diagrammatically indicated. In the illustrated example, the gumming roll 5 is located in spaced relation to and beneath a second roll 9 which for convenience of description may be termed a "reversing roll" and which may form part of a feeding means and co-operate with a feed roller 10; the rolls 9 and 10 may also be journaled in the machine in any usual and well-known way. In addition to their other functions, the rolls 9 and 10 serve to develop a feeding action and pressure upon the elements 11 to which the sheets of paper 8 or other equivalent are to be pasted, a bed or other suitable support 12 being provided for guiding the elements 11 between the rolls 9 and 10. The elements 11 may exemplify paper box blanks or any other material or devices customarily operated on by gumming machines of the type in question for the purpose of adhesively combining therewith the sheets of paper 8 or other equivalent. A suitably operated conveying belt 13 or equivalent means may be located in receiving relation to the rolls 9 and 10 for the purpose of receiving the combined elements 11 and sheets 8 or their equivalent and transferring them to other mechanisms or to other positions for further disposition depending upon the nature of the work being done.

The illustrated novel pick-off means comprises a deflecting device which in practice occupies a stationary position, and a spring controlled pick-off device movable relatively to said deflecting device in operative relation thereto. The deflecting device consists of an arm 14 fixed for instance by means of a set screw 14^a, upon a suitable stationary support illustrated in the form of a rod 15 conveniently mounted in the machine of which it forms a part. In the example shown the rod 15 is located in spaced parallel relation to the rolls 5 and 9 with the arm 14 extending from said rod toward the reversing roll 9 and provided at its free end with a deflector 16; the latter is preferably adjustably mounted on the arm 14 for instance by means of screws 17 and slots 18 and is provided with a curved deflecting edge 19 located in spaced proximity to the surface of the reversing roll 9. The pick-off device is pivotally

carried by the rod 15 so as to be capable of pivotal movement relative to the deflecting device and in the illustrated arrangement includes a lever 20 pivotally mounted upon a hub 21 which forms an integral part of the arm 14, as clearly shown in Fig. 3; any suitable means may be provided for maintaining the lever 20 in position upon the hub 21, as for instance a collar 22 secured in place by means of a set screw 23. The lever 20 at its free end carries a pick-off member 24 which projects from said lever 20 toward the gumming roll 5 and is adjustably secured to said lever, for instance by means of screws 25 and slots 26, as shown in Fig. 1.

15 The pick-off member 24 terminates in a tapered free end consisting of a lower curved edge 27 conforming to and resting upon the surface of the gumming roll 5 in the operative position of the parts, and an upper straight edge 28 extending in an upward inclination in a return direction from said surface of the gumming roll 5 toward the deflecting edge 19. The lever 20 is acted upon by a spring 29 in a manner to yieldingly maintain the lower curved edge 27 of the pick-off member 24 in engagement with the gumming roll 5, as illustrated in Fig. 1. The preferred arrangement further includes an adjustable means for determining the position of the deflecting edge 19 relatively to the roll 9, this adjustable means being shown in the drawing in the form of a screw 30 in threaded engagement with the arm 14 and terminating upwardly beyond the same in a squared end 31 or equivalent means for facilitating the manipulation of said adjusting screw 30; a lock nut 32 is preferably provided for fixing the screw 30 in an adjusted position. The screw 30 rests upon and bears against a stationary member 33 forming part of the gumming machine and suitably located in co-operative position beneath the screw 30, as shown in Fig. 1. It will be obvious, by suitably manipulating the screw 30, that the arm 14 and its associated elements may be pivotally adjusted about the rod 15 to set the deflecting edge 19 in any predetermined or desired relation to the reversing roll 9, within the range of the arrangement.

40 In practice the pick-off means consists of a unit comprising the stationary deflecting device and the spring pressed pick-off device located in co-operative relation to said deflecting device, as illustrated in Fig. 2, the pick-off device being pivotally movable relatively to the deflecting device. It will be understood that a plurality of such units in the number required for efficient 45 operation, are located in the gumming machine at spaced intervals lengthwise of the rolls 5 and 9 or their equivalent.

45 In operation the sheets of paper 8 or other material are fed to the gumming roll 5 and picked up by the adhesive coated surface thereof as illustrated in Fig. 1, said sheets 8 or their equivalent in their travel over the roll 5 being coated with adhesive on the one surface by the action of said gumming roll 5. As the sheets 8 reach the 50 pick-off members 24, said sheets 8 or their equivalent will be stripped from the surface of the gumming roll 5 and by the action of the straight upper edges 28 of the pick-off member will be guided to the deflecting edges 19. These edges 55 will divert the travel of the sheets 8 or their equivalent in the manner indicated in Fig. 1, and will finally bring the adhesive coated surfaces of said sheets 8 or their equivalent into contact with the elements 11. The sheets 8 adhering to the elements 11 will pass between the rollers 60

5 and 10 in the illustrated example of the machine so that by the action of the said rolls 9 and 10 the sheets 8 will be securely pasted in surface contact with the elements 11. The combined elements 11 and sheets 8 will then pass to the conveyor belt 13 for further operative steps or to another point for further disposition.

5 The curved lower surface 27 of the pick-off member 24 provides an efficient support for said member and maintains the pick-off device in a position of maximum efficiency. At the same time this curved lower surface 27 reduces the tendency of the point of the pick-off member 24 to wear down and consequently materially reduces the necessity for replacement. When replacement is 10 required the lever 20 and the associated pick-off member 24 may be easily removed as an independent unit to make this possible. As supports such as the rod 15 are generally supported in the machine in a manner to be easily removable, 15 the detachment of the lever 20 therefrom may be easily accomplished whenever the aforesaid replacement becomes necessary. An important feature of the novel arrangement resides in the fact that any wear on the pick-off member 24 does 20 not effect the operative relation of the deflector means and more particularly the deflector edge 19 thereof, relatively to the reversing roll 9. This is due to the fact that the deflecting device and the pick-off device comprise independent members of which the deflecting device is stationary and the pick-off device is capable of movement relatively thereto. The novel pick-off means is 25 extremely simple in construction and economical to produce and requires no skilled supervision in 30 its operation or maintenance.

35 Various changes in the specific forms shown and described may be made within the scope of the claims without departing from the spirit of the invention.

40 I claim:

1. In a gumming machine including a gumming roll and a reversing roll, that improvement which comprises a pick-off device consisting of a supporting rod in spaced parallel relation to said 45 rolls, an arm fixed on said rod and extending therefrom toward said reversing roll, a deflector adjustably mounted on said arm and having a curved deflecting edge located in spaced proximity to the surface of the reversing roll, a stationary member, an adjustable stop carried by said arm and engaging said stationary member for determining the position of said deflecting edge relatively to said reversing roll, a hub forming an integral part of said arm, a lever pivotally mounted on said hub, a pick-off member adjustably carried by said lever and projecting 50 therefrom toward said gumming roll, said pick-off member having a tapered free end consisting of a lower curved edge conforming to and resting upon the surface of said gumming roll and an upper straight edge extending in an upward inclination from said surface of the gumming roll in a direction toward said deflecting edge, a spring 55 acting on said pick-off member for yieldingly maintaining the lower curved edge thereof in engagement with said gumming roll, and a collar fixed on said hub for maintaining said lever in place thereon.

60 2. In a gumming machine including a gumming roll and a reversing roll, that improvement which comprises a pick-off device consisting of a supporting rod in spaced parallel relation to said 65 rolls, a deflecting device fixed upon said rod and 70

5 having a curved deflecting edge located in spaced proximity to the surface of said reversing roll, adjustable means for determining the position of said deflecting edge relatively to said reversing roll, a pick-off device mounted on said rod and pivotally movable relatively thereto, said pick-off device having a tapered free end consisting of a lower curved edge conforming to and resting upon the surface of said gumming roll and an upper straight edge extending in an upward inclination from said surface of the gumming roll in a direction toward said deflecting edge, and a spring 10 acting on said pick-off device to yieldingly maintain the lower curved edge thereof in engagement with said gumming roll.

10 3. In a gumming machine including a gumming roll and a reversing roll, that improvement which comprises a pick-off device consisting of a supporting rod in spaced parallel relation to said rolls, a deflecting device fixed upon said rod and having a curved deflecting edge located in spaced proximity to the surface of said reversing roll, a pick-off device pivotally carried by said rod and having a tapered free end consisting of a lower curved edge conforming to and resting upon the surface of said gumming roll and an upper straight edge inclined in a return direction from 15 said surface of the gumming roll, and a spring 20

20 25

25 acting on said pick-off device to yieldingly maintain the lower curved edge thereof in engagement with said gumming roll.

4. A pick-off means of the kind described comprising a stationary deflecting device provided with a curved deflecting edge at its free end, a hub forming an integral part of said deflecting device, a pick-off device pivotally mounted on said hub and pivotally movable relatively to said deflecting device, said pick-off device having a 10 tapered free end consisting of a curved lower edge and a straight upper edge inclined upwardly in a return direction toward said deflecting edge, and a spring acting on said pick-off device to yieldingly force the same in a given direction. 15

5. A pick-off means of the kind described comprising a stationary deflecting device provided with a curved deflecting edge at its free end, and a spring pressed pick-off device pivotally movable relatively to said deflecting device and having a tapered free end consisting of a curved edge and a straight edge inclined in a return direction 20 relatively to said curved edge.

6. In a pick-off means of the kind described, the combination of a stationary deflecting device, 25 and a spring pressed pick-off device in co-operative relation with said deflecting device and pivotally movable relatively thereto.

GEORGE W. von HOFE.
